COMBINED LAVATORY, WATER CLOSET AND CABINET

James A. Tiller, Louisville, Ky., assignor to American
Radiator & Standard Sanitary Corporation, New York,
N.Y., a corporation of Delaware

Filed Aug. 8, 1961, Ser. No. 66,251

Term of patent 14 years

(Cl. D4—2)

FIG.1

FIG.2

FIGURE 1 is a view in perspective of a combined lavatory, water closet and cabinet showing my new design.

FIGURE 2 is a fragmentary front view showing a portion of the left side of the lavatory cabinet and a portion of the area to the left thereof.

The rear and side of the cabinet not shown are substantially plain. The side of the cabinet not shown is substantially identical to that shown, except as indicated. The side of the water closet not shown is substantially identical to the side shown.

The side of the interior of the lavatory bowl not shown is substantially like the side which is shown.

The dominant features of the design reside in the portions shown in the full lines.

I claim:

The ornamental design for a combined lavatory, water closet and cabinet, substantially as shown and described.
